UNITED STATES PATENT OFFICE.

WILLIAM W. HICKS, OF BUTLER, OKLAHOMA.

RAILROAD-TIE.

No. 920,953.

Specification of Letters Patent.

Patented May 11, 1909.

Application filed October 16, 1908. Serial No. 458,032.

To all whom it may concern:

Be it known that I, WILLIAM W. HICKS, a citizen of the United States, residing at Butler, in the county of Custer, State of Oklahoma, have invented certain new and useful Improvements in Railroad-Ties; and I do hereby declare the following to be a full, clear, and exact description of the invention, such as will enable others skilled in the art 10 to which it appertains to make and use the same.

This invention relates to railroad ties and more particularly to metallic ties.

The principal object of the invention is to 15 provide an improved form of metallic tie which shall be so arranged as to prevent creeping and other displacement of the rails.

Another object of the invention is to provide such a tie with resilient means to absorb the shock incidental to the movement 20 of rolling stock over the rails.

A still further object of the invention is to provide an improved form of composite tie comprising an outer metallic shell and an inner cement filling.

With the above and other objects in view, the invention consists in general of a tie comprising an outer metallic shell, a removable closure, a cement filling and bolts 30 disposed to project through apertures in the flanges of rails to be carried on the tie.

The invention further consists in certain novel arrangements of details and combinations of parts hereinafter fully described, 35 illustrated in the accompanying drawings and specifically set forth in the claims.

In the accompanying drawings, like characters of reference indicate like parts in the several views, and Figure 1 is a vertical longitudinal section through a tie constructed 40 in accordance with this invention, the rails being shown attached thereto. Fig. 2 is a top plan view thereof. Fig. 3 is a detail horizontal section of the closure at one end 45 of the tie. Fig. 4 is an elevation of this end. Fig. 5 is a detail showing a modified manner of securing the rail to the tie.

The numeral 10 indicates the metallic casing of the tie which is in the form of a box 50 open at one end and provided at this end with lateral flanges 11. A closure 12 is provided for this end and is preferably rabbeted to fit slightly within the body of the casing. Both of flanges 11 and closure 12 are provided with suitable apertures for the reception 55 of the bolts 13 which serve to hold the

closure in position. Bolts 14 are held in suitable apertures formed in the top and bottom surfaces of the tie, said bolts being properly positioned with reference to the gage of the road so that the bolts will, when the rail is in position extend through the flange of such rail. In the present instance the rail is indicated at 15 and the flange thereof with the bolts projecting through is shown at 16. 60 The flange 16 is provided with suitable apertures to receive the bolts 14.

The bolts having been positioned through the casing 10, the inside of the casing is filled with concrete as indicated at 17. This 70 serves to hold the bolts in position in the casing and at the same time makes a solid tie. After the concrete has been inserted the closure 12 is applied and the tie is then ready for use.

In the preferred form of this device the bolts 14 extend a considerable distance above the top of the tie. Between the base flange 16 and the top of the tie is carried a spring plate 18 provided with perforations or apertures 19 adapted to receive the ends of the bolts 14. By these means the spring plate 80 85 85 is held securely in position relative to the tie and rail. This spring plate is so proportioned that it will absorb the shock incidental to the rolling stock without danger of throwing the rails off of the track on the rebound.

When the rail is placed in position the usual nuts and washers 20 are applied to the 90 ends of the bolts 14 and the parts drawn firmly into contact. The spring plate, during this operation, is placed under sufficient tension to act as a spring nut lock for the bolts, and they are thus prevented from unscrewing.

It will be obvious that by reason of the rail being bolted directly through the flanges no creeping of the same will be possible.

There has thus been provided a tie of 100 rigid construction which will have a long life, and will prevent creeping or other displacement of the rails.

Having thus described the invention, what is claimed as new is:

1. In a railroad tie, a metallic casing, a closure therefor, bolts extending through said tie spaced to enter openings in a rail flange, and springs held on said bolts to support the rail.
2. In a railroad tie, a metallic casing, a closure therefor, a cement filling, bolts ex-

tending through said tie spaced to enter openings in a rail flange, springs provided with apertures to receive said bolts held on the bolts to support the rail.

5 3. In a railroad tie, a metallic casing, a closure therefor, a cement filling, bolts extending through said tie to secure said rail, and springs provided with apertures to re-

ceive said bolts, held on the bolts to support the rails.

In testimony whereof, I affix my signature, in presence of two witnesses.

WILLIAM W. HICKS.
